[57] ABSTRACT

Game apparatus includes a body having an opening and a bore extending from the opening to the interior of the body, a cylinder piece slidably insertable in the

bore and rotatable therein, and an electrical circuit which includes first and second conductors disposed on the side wall of the bore, a third conductor disposed on the side wall of the cylinder piece, an electrically actuatable indicator, first and second switches disposed on the end wall of the bore, and an option switch having first and second positions. Removal of the cylinder piece by sliding it from the bore after it has been rotated to any position within a certain range of positions causes the third conductor to simultaneously contact the first and second conductors and thereby actuate the indicator. Removal of the cylinder piece after it has been rotated to any position within a second range of positions results in the third conductor contacting only the first conductor so that the indicator is not actuated. After removal of the cylinder piece, the first and second switches may be manually operated. Operation of the first switch when the option switch is in the first position causes actuation of the indicator whereas operation of the second switch when the option switch is in the first position disables the indicator. When the option switch is in the second position, operation of the first switch disables the indicator and operation of the second switch actuates the indicator.

FIG. 5

ELECTRICAL GAME APPARATUS

BACKGROUND OF THE INVENTION

This invention relates in general to game apparatus and more particularly to a game whose object is to remove a certain game piece without actuating an indicator.

SUMMARY OF THE INVENTION

The game apparatus of the present invention includes a body member having an opening therein and a substantially cylindrical bore extending from the opening to the interior of the body member. A substantially cylindrical member is slidably insertable in the bore and rotatable therein. First and second electrical conductors are disposed on the side wall of the bore in spaced relationship and a third electrical conductor is disposed on the side wall of the cylindrical member. When the cylindrical member is rotatably positioned within a certain range of positions and removed from the bore, the third electrical conductor simultaneously contacts the first and second electrical conductors to cause actuation of an electrical indicator.

DESCRIPTION OF THE DRAWING

FIG. 1 shows an exploded perspective view of game apparatus made in accordance with the principles of the present invention.

FIG. 2 shows a front elevational view of the game apparatus with the propeller, propeller shaft and nose cover removed.

FIG. 3 shows a front elevational view of the game apparatus with the propeller, propeller shaft, nose cover and cylinder removed.

FIG. 4 is a fragmentary, side cross-sectional view of the game apparatus taken along line 1-1 of FIG. 2 and showing the cylinder and propeller shaft inserted in the bore.

FIG. 5 is a schematic representation of illustrative circuitry utilized in the game apparatus made in accordance with the principles of the present invention.

DETAILED DESCRIPTION

The game apparatus of the present invention, as shown in FIG. 1, includes a body member 2 shaped generally like a rocket in which certain circuit components are mounted. A portion of the interior of the body member 2 is hollowed out in order to place the components therein. The game apparatus also includes a base 4 on which the body member 2 is mounted. The base 4 is provided to maintain the body member 2 in a substantially horizontal position when the apparatus is placed on a horizontal surface.

The body member 2 has a substantially circular opening 6 located at one end thereof and a substantially cylindrical bore extending from the opening 6 to the interior of the body member 2. The bore terminates at an end wall 8 as shown in FIG. 4. Three switches 16A, 16B, and 16C (FIG. 3) are disposed on the end wall 8 of the bore 7 so that manually operable switch levers of the switches extend outwardly from the wall 8 into the bore 7. The end wall 8 has an opening 18 extending through the end wall to the interior of the body member 2 and located at a position substantially coincident with the axis of the bore 7 (see FIGS. 3 and 4).

The game apparatus also includes a cylinder 10 having an interior bore 12 extending the length of the cyl-

inder in a direction substantially parallel to the direction of the axis of the cylinder. The dimensions of the outer wall of the cylinder 10 and of the side wall of the bore 7 of the body member 2 are such as to enable the cylinder 10 to be inserted in the bore 7 of the body member 2 and to be rotated therein. The diameter of the bore 12 of the cylinder 10 is substantially uniform except for a certain portion 14 at one end of the cylinder 10 which has an expanded diameter (see FIG. 4).

The cylinder 10 may be inserted into the bore 7 until the end portion of the cylinder (having the expanded bore portion 14) contacts the end wall 8. Because of the expanded portion 14 of the bore 12, none of the levers of switches 16A, 16B or 16C contact the cylinder 10. Mounted on the end wall of the cylinder 10 (opposite the expanded portion) are two spaced pins extending just out from the cylinder end wall to enable a player to seize the pins to remove or rotate the cylinder 10.

The game apparatus further includes a substantially circular nose plate 20 of substantially uniform thickness, the outer circumference of the nose plate tapering from a maximum dimension at the back side 22 of the plate to a minimum dimension at the front side 24 of the plate 20. The nose plate 20 also has a bore extending therethrough in a direction substantially perpendicular with the planes defined by the front and back sides of the plate 20.

A cylindrical propeller shaft 26 has an outer circumference of a dimension sufficient to allow the shaft to be inserted through the bore of the nose plate 20 and the bore 12 of the cylinder 10. Disposed on one end of the propeller shaft 26 is a switch actuating pin 28 having a small spherical head supported by a shank attached to the end of the shaft 26. The head of the switch actuating pin 28 is of a sufficient dimension to allow the head to be inserted through the opening 18 of the back wall 8 to engage and open a spring switch 30 (see FIG. 4). The other end of the propeller shaft 26 has a threaded bore 32 to enable a screw 34 to be screwed into the bore. A propeller 36 has a bore 38 coincident with the axis of rotation of the propeller to enable the screw 34 to be inserted therethrough.

Assembly of the above-described components of the game apparatus is indicated by the exploded view of the apparatus shown in FIG. 1. That is, the cylinder 10 is inserted in the bore 7 of the body member 2 until the end portion of the cylinder contacts the end wall 8. The propeller shaft 26 is inserted through the bore of the nose plate 20 and through the bore 12 of the cylinder 10 so that the switch actuating pin 28 is guided through the opening 18 to contact and open the spring switch 30. (When the switch actuating pin 28 is removed from the opening 18, the spring switch 30 closes because of the spring action of contact 29 of the switch.) The screw 34 is inserted through the bore 38 of the propeller 36 and then screwed into the threaded bore 32 of the propeller shaft 26. When assembled in this fashion, the propeller 36 prevents removal of the nose plate 20 and thus removal of the cylinder 10 unless the propeller shaft 26 with the propeller 36 attached is removed or unless the propeller 36 itself is removed from the propeller shaft 26. The significance of this will be discussed later. The body member 2, cylinder 10 and shaft 26 might illustratively be constructed of wood, plastic or other suitable electrically nonconductive material. The nose plate 20 and propeller 36 might illustratively

be constructed of material which is either conductive or nonconductive.

The bulk of an electrical circuit, the schematic of which is shown in FIG. 5, is housed in the body member 2. Access to the circuit is provided by way of a hinged cover 72 shown by dotted lines in FIG. 1. This access is obtained simply by lifting the cover 72 so that it pivots about a hinge 74. The circuit includes a length of conductor 47 disposed on the side wall of the cylinder 10 so as to encircle all but a portion of the cylinder. The ends of the conductor 47 might illustratively be embedded in the cylinder to secure the conductor thereto. The path of the conductor 47 defines a plane which is substantially perpendicular to the axis of the cylinder 10. Additional lengths of conductors 40, 42, 44 and 46 are disposed on the side wall of the bore 7 and extend from the opening 6 a predetermined distance along the side wall in a direction substantially parallel with the axis of the bore 7. After this predetermined distance, the conductors 40-46 are directed into the side wall of the bore 7 to extend through the body member 2 to the hollowed-out interior portion of the body member (as shown for conductors 40 and 44 in FIG. 4). When the cylinder 10 is fully inserted into the bore 7, the conductor 47 is positioned beyond the locus of points at which the conductors 40, 42, 44 and 46 are directed into the side wall, so that the conductor 47 contacts none of the conductors 40-46 when the cylinder 10 is so positioned.

The conductors 40-46 and 47 are shown schematically in FIG. 5 as leads 40-46 and 47 respectively. Leads 42, 44 and 46 are connected respectively to stationary contacts C, B and A of a tier 48a of a two-tier switch 48. The movable contact of tier 48a of the switch 48 is connected in series with a motor 70 and a red light-emitting lamp 60. The movable contact adjustment knob of switch 48, the motor 70 and the lamp 60 are also shown in FIG. 1 as they might illustratively be disposed in the body member 2. The motor 70 is mechanically connected with a flag assembly 74 and with a cam of a cam switch 76. As shown in FIG. 1, the drive shaft of the motor 70 includes a crank 73 journaled to an arm 78. The other end of the arm 78 is hingedly connected to an extension of a wheel 80. The wheel 80 is mounted on the cover 72 so as to rotate between a "non-alarm" and "alarm" positions as the extension of the wheel is moved vertically by the arm 78 in response to rotation of the drive shaft of the motor 70. It should be noted here that in order to raise the cover 72, the arm 78 would first be detached either from the extension of the wheel 80 or from the crank 73 of the drive shaft of the motor 70.

Referring again to FIG. 5, switches 16A, 16B and 16C are connected respectively to stationary contacts A, B and C of tier 48b of switch 48. The movable contact of tier 48b of switch 48 (which is mechanically ganged to the movable contact of the tier 48a) is connected to a power source 84 (e.g., batteries as shown in FIG. 1). The switches 16A, 16B and 16C are also connected in parallel to various other elements of the circuit including the lamp 60, the wiper element of the cam switch 76, a green light-emitting lamp 62 and an on/off switch 86. The lamp 62 and on/off switch 86 are also shown in FIG. 1 as they might illustratively be disposed in the body member 2.

The circuit of FIG. 5 further includes a spring switch 30, referred to earlier in conjunction with FIG. 4, and

a pendulum switch 50 connected in parallel with conductors 40-46. As shown in FIG. 1, the pendulum switch 50 includes a length of electrical conductor 56 having a weight 58 attached to one end thereof, the other end being pivotally attached to a frame 52 in such a manner that the conductor 56 and weight 58 are free to swing in substantially any direction from the vertical. A circular conductor 54 encircles the conductor 56. The frame 52 is mounted in the body member 2 so that when the game apparatus is substantially horizontal, the conductor 56 and weight 58 are suspended in a substantially vertical orientation through the circular conductor 54 so that the conductor 56 is not touching the conductor 54. The object and operation of the game apparatus will now be described.

The object of the game apparatus is to "disarm" it, i.e., to "open circuit" the game apparatus circuitry, by operating the appropriate one of switches 16A-16C without actuating the lamp 60 and the motor 70. If the on/off switch 86 is in the "on" position, then operation of either of the switches 30 or 50, or operation of any one of a possible two of the switches 16A-16C, or contact of conductor 47 simultaneously with conductor 40 and a particular one of the conductors 42, 44 and 46 will cause the lamp 60 to be lighted and the motor 70 to operate. Assume, for example, that the movable contact of switch 48 is placed on stationary contact C and that switches 16A-16C are in the positions shown in FIG. 5. Under these conditions, if the game apparatus is disturbed or "tilted," the conductor 56 and weight 58 of the pendulum switch 50 may be caused to swing so that the conductor 56 makes contact with the conductor 54 in which case a circuit is closed for supplying power from the power supply 84 to the lamp 60 and motor 70. Specifically, power would be supplied by the power supply 84 via tier 48b of the switch 48 and via switch 16C to the lamp 60 and motor 70 and from there via the pendulum switch 50 and the on/off switch 86 to ground. The lamp 60 would thus be lighted and the motor 70 would be caused to operate.

Similarly, if the spring switch 30 were caused to close by removal of the switch actuating pin 28 from the opening 18, the lamp 60 and motor 70 circuit would again be closed.

Whether contact of the conductor 47 simultaneously with the conductor 40 and one of the conductors 42, 44 or 46 causes lighting of the lamp 60 and operation of the motor 70 depends on the setting of the switch 48. Thus, if the movable contacts of the switch 48 are closed on the stationary contact C, then contact of the conductor 47 simultaneously with conductors 40 and 42 would close the circuit of the lamp 60 and motor 70. However, contact of the conductor 47 simultaneously with conductor 40 and either of conductors 44 or 46 would not close the circuit of the lamp 60 and motor 70. As indicated earlier, when the cylinder 10 is fully inserted into the bore 7, the conductor 47 contacts none of the conductors 40-46. However, during removal of the cylinder 10 from the bore 7, the conductor 47 will simultaneously contact conductor 40 (consisting of two lengths of conductor spaced apart as shown in FIG. 1 and at least two of the three conductors 42-46. The two lengths comprising conductor 40 are spaced apart sufficiently so that as the cylinder 10 is removed, conductor 47 will contact at least one of these lengths. That is, the spacing between the two lengths of conductor 40 is greater than the distance be-

tween the ends of conductor 47, i.e., the portion of the cylinder 10 not encircled by the conductor 47.

The object of the game apparatus is to rotationally position the cylinder 10 in the bore 7 so that when the cylinder is slidably removed from the bore, the conductor 47 will not contact that certain conductor connected to the stationary contact of switch 48 at which the movable contact of the switch is positioned. In such case, the lamp 60 would not be lighted and the motor 70 would not be operated. This would occur, of course, when that portion of the cylinder not encircled by the conductor 47 were contiguous with that certain one of the conductors 42-46 as the cylinder were being removed from the bore 7.

The end of the body member 2 at which the bore 7 is located might illustratively include identifying marks inscribed about the opening 6 such as shown in FIG. 2. The three marks that are shown are the letters A, B and C, each being located adjacent a different one of the conductors 42, 44 and 46 terminations. The cylinder 10 might illustratively include a mark such as the arrow 90 shown in FIG. 2 inscribed on one end of the cylinder near the perimeter of the circle defined by the side wall of the cylinder. The arrow 90 is located to point to that portion of the side wall of the cylinder which is not circumscribed by the conductor 47. By rotatably positioning the cylinder 10 when it is inserted in the bore 7 so that the arrow 90 is contiguous with one of the marks A, B or C inscribed about the opening 6, the conductor 47 is positioned so as not to contact a selected one of the conductors 46, 44 or 42 respectively. If the appropriate one of such conductors is selected (depending on the setting of the switch 48), the cylinder 10 may be slidably removed from the bore 7 so that the circuit of the lamp 60 and motor 70 will not be closed.

The final way in which the circuit of the lamp 60 and motor 70 may be closed is by the operation of any but a particular one of the switches 16A, 16B or 16C. That is, depending upon the setting of switch 48, operation of any but one of the switches 16A-16C will cause the lamp 60 to be lighted and the motor 70 to operate. For example, referring to FIG. 5, when the movable contact of the tier 48b of switch 48 is closed on stationary contact C, operation of either switch 16A or 16B would close the circuit of the lamp 60 and motor 70. This can be illustrated by assuming that switch 16B is operated in which case the movable contact element 92 of the switch would be moved from the left to the right (FIG. 5) causing contacts b and c of the switch 16B to be electrically connected and contacts e and f of the switch to be electrically connected. (Note that movement of the movable contact element 92 would be effected by throwing the lever of the switch 16B shown in FIG. 3). Operation of the switch 16B causes power to be supplied by the power supply 84 via tier 48b of the switch 48 and via switch 16C to the lamp 60 and motor 70 and from there via a conductor 94 to contact e of switch 16B and through movable element 92 to contact f of the switch 16B, and via the on/off switch 86 to ground. The lamp 60 is thus lighted and the motor 70 is caused to operate. Operation of switch 16A under the same circumstances would also cause the lamp 60 to be lighted and the motor 70 to operate.

Operation of switch 16C when the movable contact of switch 48 is closed on stationary contact C, however, "open circuits" the lamp 60 and motor 70 circuit and in addition causes the lamp 62 to be lighted. Thus,

when the movable contact element 96 of switch 16C is moved to its rightmost position (FIG. 5), the circuit from the power supply 84 to the lamp 60 and motor 70 is open since contacts a and b of the switch 16C are no longer electrically connected. On the other hand, since contact b and c of the switch 16C are now electrically connected, power flows from the power supply 84 via the tier 48b through the switch 16C to the lamp 62 and thence via the on/off switch 86 to ground causing the lamp 62 to be lighted.

After the circuit of the motor 70 is closed by any one of the actions described above, the motor commences to turn the cam of the cam switch 76 so that the cam contacts a wiper element 77 providing another path for closing the circuit of the motor 70 to ground. Thus, once the cam of the cam switch 76 engages the wiper element 77, the motor will continue to operate even though the switch which triggered the operation of the motor is again opened. However, if the switch which triggered the operation of the motor 70 is opened before the cam of the cam switch 76 rotates to the point where it is in contact with the wiper element 77, the motor 70 will be stopped. As indicated earlier, operation of the motor causes a flag 75 to be raised to an "alarm" position.

To briefly summarize, the object of using the game apparatus of the present invention is to gain access to and operate a particular one of the switches 16A-16C so as to "deactivate" the apparatus circuitry and to light a lamp 62 without closing any of the other switches which will cause the lamp 60 to be lighted and the motor 70 to operate. In order to get access to the switches 16A-16C, it is necessary to remove the propeller 36 from the propeller shaft 26 so that the nose plate 20 can be removed from about the propeller shaft 26 and the cylinder 10 can be removed from the bore 7. In order that the lamp 60 and motor 70 not be actuated, the switch actuating pin 28 of the shaft 26 must not be removed from the opening 18 in the back wall 8, otherwise the spring switch 30 will close causing actuation of the lamp and motor. Removal of the cylinder 10 so that the lamp 60 and motor 70 circuit are not closed requires that the cylinder be rotatably positioned within certain ranges of positions so that the conductor 47 does not simultaneously contact conductor 40 and a particular one of conductors 42-46, the particular one of the latter being determined by the setting of switch 48. If the cylinder 10 is removed so that the conductor 47 does not contact the particular one of the conductors 42-46, then the lamp 60 and motor 70 circuit will not be closed. If during any of this activity, the game apparatus is overly disturbed or jostled, the pendulum switch 50 may be caused to close so that the lamp 60 and motor 70 circuit is closed. If the cylinder 10 is successfully removed from the bore 7, the appropriate one of switches 16A-16C disposed on the end wall 8 of the bore 7 must be operated to "deactivate" the game apparatus circuitry. Depending upon the setting of the switch 48, operation of a particular one of the switches 16A-16C will "deactivate" the game apparatus circuitry and cause the green lamp 62 to be lighted. Operation of either of the other two switches, however, would cause the lamp 60 to be lighted and the motor 70 to operate.

It is to be understood that the above-described embodiment is only illustrative of the application of the principles of the present invention. Numerous other ar-

rangements and embodiments may be devised by those skilled in the art without departing from the spirit and scope of the invention. For example, any number of switches such as the switches 16A-16C and conductors such as conductors 42-46 might be employed in the game apparatus.

What is claimed is:

1. Game apparatus comprising:

a body member having an opening therein and a substantially cylindrical bore extending from the opening to the interior of the body member; 10
a substantially cylindrical member slidably insertable in the bore so that the axis of the bore is substantially parallel to the axis of the cylindrical member, the cylindrical member being rotatable about its axis when inserted in the bore; 15
a first electrically actuatable indicating means; and an electrical circuit including first and second conductive means disposed on the side wall of the bore in spaced relationship and third conductive means disposed on the side wall of the cylindrical member so as to simultaneously contact said first and second means to actuate said indicating means when said cylindrical member is rotatably positioned within a certain range of positions and removed 25 from the bore.

2. Game apparatus as in claim 1 wherein said electrical circuit further includes a fourth conductive means disposed on the side wall of the bore and an option switch having first and second positions, said option switch enabling actuation of said indicating means upon the contact of said third conductive means simultaneously with said first and second conductive means if said switch is in the first position and enabling actuation of said indicating means upon the contact of said third conductive means simultaneously with said first and fourth conductive means if said switch is in the second position, contact of said third conductive means simultaneously with said first and fourth conductive means occurring when said cylindrical member is rotatably positioned within a second range of positions and removed from the bore.

3. Game apparatus as in claim 2 wherein said cylindrical member has a first mark inscribed on one end thereof near the perimeter of the circle defined by the side wall of the cylindrical member, wherein the body member has second and third marks inscribed therein about the opening and designating the location of the second and fourth conductive means respectively on the side wall of the bore, and wherein the third conductive means is disposed on the cylindrical member relative to the position of said first mark such that when the cylindrical member is rotatably positioned in the bore so that the first mark is contiguous with the second mark, removal of the cylindrical member from the bore causes the third conductive means to simultaneously contact the first and fourth conductive means, and when the cylindrical member is rotatably positioned in the bore so that the first mark is contiguous with the third mark, removal of the cylindrical member from the bore causes the third conductive means to simultaneously contact the first and second conductive means.

4. Game apparatus as in claim 1 wherein said electrical circuit further includes a second electrically actuatable indicating means and a manually operable dis-

ing switch having first and second conditions and disposed on the end wall of the bore so as to be accessible only when the cylindrical member is removed from the bore, said disarming switch being operable when placed in the second condition to cause actuation of said second indicating means and to disable actuation of said first indicating means.

5. Game apparatus as in claim 1 wherein said electrical circuit further includes

a second electrically actuatable indicating means, first and second manually operable disarming switches, each having first and second conditions and each disposed on the end wall of the bore so as to be accessible only when the cylindrical member is removed from the bore, and an option switch having first and second conditions, said first disarming switch being operable when placed in the first condition and when said option switch is in the first condition to cause actuation of said second indicating means and to disable actuation of said first indicating means and being operable when placed in the first condition and when said option switch is in the second condition to cause actuation of said first indicating means, and said second disarming switch being operable when placed in the first condition and when said option switch is in the second condition to cause actuation of said second indicating means and to disable actuation of said first indicating means.

6. Game apparatus as in claim 1 further including a

35 frame mounted in said body member and wherein said electrical circuit further includes a switch comprising a pendulum contact element vertically suspended from said frame and movable from the vertical when the body member is disturbed, and a stationary contact element mounted in said body member and circumscribing said pendulum contact element, said switch being operable to actuate said first indicating means when said pendulum contact element is caused to move and contact said stationary contact element.

40 7. Game apparatus as in claim 1 wherein said cylindrical member has an interior bore extending the length of the cylindrical member in a direction substantially parallel to the direction of the axis of said cylindrical member, said game apparatus further including

50 a shaft slidably insertable in the bore of said cylindrical member, an end member mountable on one end of said shaft to prevent movement of said cylindrical member in the direction of said one end when the shaft is inserted in the bore of said cylindrical member and the end member is mounted on the shaft, and a switch actuating means mounted on the other end of said shaft, and wherein said electrical circuit includes a switch disposed in the end wall of the bore of the body member for receiving the switch actuating means, said switch causing actuation of said indicating means when the switch actuating means is removed therefrom.

60 8. Game apparatus as in claim 1 wherein said first indicating means comprises a flag element movable between a first and second positions and normally positioned in said first position and an electric motor for causing said flag element to move from the first position to the second position.

9. Game apparatus as in claim 1 wherein said first indicating means is an electric lamp.

10. Game apparatus as in claim 1 wherein said first and second conductive means comprise longitudinal conductors each extending from the opening of the body member along a portion of the side wall of the bore in a direction substantially parallel with the axis of the bore, and wherein said third conductive means comprises a length of conductor encircling all but a portion of the cylindrical member to define a plane substantially perpendicular to the axis of the cylindrical member such that when the cylindrical member is inserted in the bore the plane defined by the third conductive means does not intersect the first and second conductive means and such that when the cylindrical member is removed from the bore the third conductive means will simultaneously contact the first and second conductive means unless said portion of the cylindrical member is contiguous with the second conductive means as the cylindrical member is being removed. 15

11. Game apparatus including an elongated body member comprising a front section having a substantially cylindrical bore located therein, one end of which communicates with the exterior of the body member and the other end of which terminates at an end wall of the body member, a substantially cylindrical member slidably insertable and rotatable in the bore so that the axis of the bore is substantially parallel to the axis of the cylindrical member, and an electrical circuit including first, second and third longitudinal conductors, each disposed at different locations on the side wall of the bore and extending from said one end of the bore a certain distance along the side walls in a direction substantially parallel with the axis of the bore, a fourth conductor encircling all but a portion of the cylindrical member, said fourth conductor defining a plane substantially perpendicular to the axis of the cylindri- 40

cal member such that when the cylindrical member is positioned in the bore, the fourth conductor contacts neither the first, second nor third conductors, an electrically actuatable indicating means, and an option switch having first and second positions, said fourth conductor simultaneously contacting said first and second conductor as the cylindrical member is removed from the bore after being rotatably positioned within a certain range of positions to thereby actuate said indicating means if said option switch is in said first position, and said fourth conductor simultaneously contacting said first and third conductors as the cylindrical member is removed from the bore after being rotatably positioned within a second range of positions to thereby actuate said indicating means if said option switch is in the second position.

12. Game apparatus as in claim 11 wherein said electrical circuit further includes a second electrically actuatable indicating means, first and second manually operable disarming switches, each having first and second conditions and each disposed on the end wall of the bore so as to be accessible only when the cylindrical member is removed from the bore, and an option switch having first and second conditions, said first disarming switch being operable when placed in the first condition to cause actuation of said second indicating means and to disable actuation of said first indicating means if said option switch is in the first condition, and being operable when placed in the first condition to cause actuation of said first indicating means if said option switch is in the second condition, and said second disarming switch being operable when placed in the first condition to cause actuation of said second indicating means and to disable actuation of said first indicating means if said option switch is in the second condition and being operable when placed in the first condition to cause actuation of said first indicating means if said option switch is in the first condition. 20 25 30 35
